UNITED STATES PATENT OFFICE.

TAMIS C. SCHENK, OF DETROIT, MICHIGAN.

DEVICE FOR CLAMPING TIMBERS TOGETHER.

Application filed March 30, 1922. Serial No. 548,246.

To all whom it may concern:

Be it known that I, TAMIS CORNELIS SCHENK, a subject of the Queen of the Netherlands, a resident of Detroit, in the county of Wayne and State of Michigan, have invented a certain new and useful Improvement in Devices for Clamping Timbers Together, of which the following is a specification.

10 My invention relates particularly to a device by means of which timbers, poles, etc., may be clamped together.

The object of my invention is to provide a device of this character by means of which timbers used in various kinds of construction work may be secured together so as to obviate the expense incident to cutting the timbers and the securing of the same together with spikes, nails, screws, etc. In 20 construction work it was formerly necessary, especially in the erection of scaffolding for buildings, to provide uprights connected together at their ends by first sawing the timbers the correct length and then fastening 25 them together with the aid of spikes, nails or screws. In the utilization of my invention it is not necessary to change the length of the timbers, nor is it necessary to damage them by the use of spikes, nails, screws, etc., 30 but timbers of any length can be used repeatedly in the construction of buildings of different proportions without the unnecessary labor and cost of materials found necessary previously. Still another object 35 is to provide a type clamping device such that the cost of manufacture may be reduced to a minimum.

Further objects of my invention will be seen from the detailed description thereof 40 hereinafter.

While my invention is capable of being carried out in many different ways, for the purpose of illustration I have shown only one way of carrying out the same in the accompanying drawings in which—

Figure 1 is a side elevation showing two timbers secured together with my clamping device;

Fig. 2 is a plan view of the same showing 50 the timbers in cross-section;

Fig. 3 is a plan view of a U-shaped member;

Fig. 4 is a side elevation of the locking piece used therewith, and

55 Fig. 5 is a plan view of a spanner used with my invention.

In the drawings I have shown two timbers 1 and 2 which are overlapped at their ends. These are secured together by clamping devices made in accordance with my invention. 60 Each of the clamping devices is comprised of a U-shaped bar of iron 3 provided, preferably, with straight legs 4 having at their ends hooks 5. The hooks 5 are provided so as to serve as a fulcrum for a locking piece 65 6. The locking piece 6 is formed from a flat sheet of iron, in one side of which there is a wedge-shaped depression 7 to form a lateral extension 8, the free edge of which is arranged to grip against the side of the 70 adjacent timber 2. The two lateral edges 9 at the two sides of the extension 8 serve to rest against the straight legs 3 of the U-shaped member and thus to limit the turning movement. The movement of the 75 locking piece is accomplished by the use of a spanner 10 having a slot 11 which fits over the outer edge of the locking piece 6 and is provided with a handle 12 to rotate the same in the manner hereinafter de- 80 scribed.

In applying my invention, the timbers 1 and 2 having been overlapped sufficiently to give the desired total length to the combined timbers, each of the U-shaped members 3 is 85 placed around the timbers with the hooks 5 directed downwardly. The locking piece 6 is now inserted with the straight edge in the hooks 5 and the free edge of the extension 8 located against the timber on a level 90 with the point where the other end of the the U-shaped member contacts with its adjacent timber. The spanner 10 is now inserted over the locking piece and the latter is rotated so as to move the ends of the U- 95 shaped member carrying the hooks 5 downwardly until the lateral portions 9 of the locking piece 6 rests against the straight legs 4. This movement will firmly clamp the timbers 1 and 2 together and any tendency of the upper timber 2 to move downwardly, under any excessive load, can only 100 result in tightening the clamping action of the clamping device as it would tend to increase the distance between the locking piece and the opposite end of the U-shaped member 3. The clamping action of the device is so effective, however, that normal loads will not in any way affect the relative positions of the timbers 1 and 2.

While I have described my invention above in detail, many changes may be made

within the scope of my invention and appended claims.

I claim:

1. A clamping device comprising a U-shaped member having hooks on its outer ends and a locking piece carried in said hooks, said locking piece having an extension at one side to provide a clamping edge, and lateral portions arranged to contact with the U-shaped member to limit the turning movement of the locking piece.
2. A clamping device comprising a U-shaped member having hooks on its outer ends and a sheet metal locking piece carried in said hooks, said locking piece having an upset extension at one side to provide a clamping edge, and lateral portions arranged to contact with the U-shaped member to limit the turning movement of the locking piece.
3. A clamping device comprising a U-shaped member provided with straight legs having hooks on their outer ends and a locking piece carried in said hooks, said locking piece having an extension at one side to provide a clamping edge, and lateral portions arranged to contact with the U-shaped member to limit the turning movement of the locking piece.
4. A clamping device comprising a U-shaped member provided with straight legs having hooks on their outer ends and a sheet metal locking piece carried in said hooks, said locking piece having an upset extension at one side to provide a clamping edge, and lateral portions arranged to contact with the U-shaped member to limit the turning movement of the locking piece.
5. A clamping device comprising a U-shaped member having hooks on its outer ends and a locking piece carried in said hooks, said locking piece having an extension at one side to provide a clamping edge, and lateral portions arranged to contact with the U-shaped member to limit the turning movement of the locking piece.

sion at one side to provide a clamping edge, lateral portions arranged to contact with the U-shaped member to limit the turning movement of the locking piece, and a detachable spanner provided for turning the locking piece.

6. A clamping device comprising a U-shaped member having hooks on its outer ends and a sheet metal locking piece carried in said hooks, said locking piece having an upset extension at one side to provide a clamping edge, lateral portions arranged to contact with the U-shaped member to limit the turning movement of the locking piece, and a detachable spanner provided for turning the locking piece.

7. A clamping device comprising a U-shaped member provided with straight legs having hooks on their outer ends and a locking piece carried in said hooks, said locking piece having an extension at one side to provide a clamping edge, lateral portions arranged to contact with the U-shaped member to limit the turning movement of the locking piece, and a detachable spanner provided for turning the locking piece.

8. A clamping device comprising a U-shaped member provided with straight legs having hooks on their outer ends and a sheet metal locking piece carried in said hooks, said locking piece having an upset extension at one side to provide a clamping edge, lateral portions arranged to contact with the U-shaped member to limit the turning movement of the locking piece, and a detachable spanner provided for turning the locking piece.

In testimony that I claim the foregoing, I have hereunto set my hand this 14th day of March, 1922.

TAMIS C. SCHENK.
